(57) **CLAIM**

The ornamental design for a temporary bridge as shown and described.

DESCRIPTION

FIG. 1 is a top perspective view of a temporary bridge according to the present invention;

FIG. 2 is a bottom perspective view of FIG. 1;

FIG. 3 is a front view of FIG. 1;

FIG. 4 is a rear view of FIG. 1;

FIG. 5 is a top view of FIG. 1;

FIG. 6 is a bottom view of FIG. 1;

FIG. 7 is a side view of FIG. 1; and,

FIG. 8 is a side view of FIG. 1.

The drawings contain symbolic break lines. Any portion between the break lines forms no part of the claimed design. The broken line showing is included for the purpose of illustrating unclaimed subject matter and forms no part of the claimed design.

1 Claim, 8 Drawing Sheets(56)
